UNITED STATES PATENT OFFICE.

LUCIUS T. GIBBS, OF NEW YORK, N. Y., ASSIGNOR TO VEHICLE EQUIPMENT COMPANY, OF BROOKLYN, NEW YORK, A CORPORATION OF NEW JERSEY.

WHEEL-HUB.

SPECIFICATION forming part of Letters Patent No. 700,032, dated May 13, 1902.

Application filed September 11, 1901. Serial No. 74,993. (No model.)

To all whom it may concern:

Be it known that I, LUCIUS T. GIBBS, a citizen of the United States, residing at the borough of Manhattan, in the city, county, and 5 State of New York, have invented certain new and useful Improvements in Wheel-Hubs, of which the following is a specification, reference being had to the drawings accompanying and forming a part of the same.

10 The invention which forms the subject of my present application for Letters Patent is an improvement in hubs for vehicle-wheels, the primary objects in which are the provision of means for the support of the wheel 15 bearing or box in the hub in such manner that it will be securely maintained in fixed relationship to the hub and spokes, and, secondly, to permit the ready replacing of any 20 broken without displacing any of the remaining spokes or removing the flanges of the hub.

The nature and object of my said improvement will be better understood from a consideration of the plan of construction employed in the ordinary forms of wheel-hub of 25 the general class to which the invention pertains. In such hubs it has heretofore been customary to bolt two flanges together over a wooden core, the spokes being disposed between the flanges and mortised into the 30 wooden core. The bearing or box is then driven into a hole bored through the center of the wooden core. In hubs of this general plan of construction, however, it will be noted that the bearing or box is held in position solely by the wood, so that should the latter shrink or swell the bearing or box is liable to be thrown more or less out of line. It is also impossible in such forms to replace 35 one spoke without disarranging the others while bolting the flanges. In other forms of hub which are usually cast in a single piece the spokes are driven into spoke-holes; but the practicability of this construction requires 40 the wheel to be well tired in order to keep the spokes tight in the hub. Any shrinkage of the spokes in the "drive" will cause them to become loose. In order to avoid these objections and at the same time to secure what 45 is regarded as essential in wheel-work that the lower end of the spokes should be embedded in wood, I have devised the form of hub 50 illustrated in the accompanying drawings, in which—

Figure 1 is a longitudinal central section 55 of my improved hub, and Fig. 2 an end elevation of the same.

A designates a malleable-iron or steel casting in one piece, with spoke-holes disposed symmetrically around the center flanges and 60 an inwardly-extending flange at one end. I usually cast these spoke-holes straight in section. Into this casting is pressed or driven a wooden core B, after which the hub is placed in a machine and the wooden core and 65 outer end C of the casting bored out perfectly true. At the same time the inner end of the cylindrical casting is bored out to a slightly larger diameter, as shown at D. The two surfaces C and D form supports for the bearing or box F, which is pressed into them. 70

The wooden core B has small holes E, preferably rectangular in section, mortised into it, and the inner ends of the spokes H are formed with corresponding tenons G, which 75 fit tightly into the holes E. The spokes when inserted in place are thus supported by the casting A and at their inner ends by the mortises E.

It will be seen from the above description 80 that the bearing or box F has a support at each end in the iron or steel hub, and this not only secures a stronger and truer hub, but it renders it easily possible to insert a new box or bearing when necessary or to replace a spoke whenever occasion requires by simply drawing out such as may be defective and inserting a new one in its place without displacing or disturbing any of the others. 85

Having now described my invention, what 90 I claim is—

A wheel-hub comprising in combination a single casting A, a tubular wooden core B driven or pressed into the same, the outer end of said casting having an opening equal 95 in diameter to that through the wooden core, and the inner end being of greater diameter than the core, to afford two supports for a bearing, and a box or bearing extending through the hub and supported at each end 100 by the casting, as set forth.

LUCIUS T. GIBBS.
